UNITED STATES PATENT OFFICE.

MAXIMILIAN F. BONZANO, OF PHILADELPHIA, PENNSYLVANIA.

RAIL-FASTENING.

No. 923,008.

Specification of Letters Patent. Patented May 25, 1909.

Application filed December 16, 1908. Serial No. 467,859.

To all whom it may concern:

Be it known that I, MAXIMILIAN F. BONZANO, a citizen of the United States, residing in Philadelphia, Pennsylvania, have invented 5 certain Improvements in Rail-Fastenings, of which the following is a specification.

My invention relates to means employed in connection with railroad rails to resist and prevent creeping of the same.

10 Devices to resist or prevent the rail creeping are usually applied so as to anchor the middle of the rail, and the structure forming the subject of my invention in the several embodiments indicated in the drawings will 15 be placed at one or more points with respect to a rail with the same object in view.

In my Patent No. 906,860, dated December 15, 1908, I have described an improved form of rail fastening in which a wear-plate 20 mounted upon the tie supports the rail; clips being employed to hold the rail in place, in combination with wedge blocks which maintain said clips in proper holding position with respect to the rail and wear-plate. In my 25 present invention, I propose to make use of the form of wear-plates and wedge-blocks disclosed in my prior application, with a modified form of clip which is positively secured to the rail. In one form of my present 30 structure the rail-engaging member, suitably apertured, might be employed as a splice-bar.

My invention is fully shown in the accompanying drawings, in which:

35 Figure 1, is a plan view of rail securing means showing one form of anti-creeping device embodying my invention; Fig. 2, is a sectional view of the same on the line *a—a*; Fig. 3, is a plan view illustrating a modification 40 embodying my invention; Figs. 4 and 5, are sectional views of the same on the line *b—b* and *c—c*, respectively; Fig. 6, is a view illustrating a further modification embodying 45 my invention; Fig. 7, is a perspective view of the form of combined clip and anti-creeping device shown in Figs. 1 and 2; Fig. 8, is a perspective view of the form of combined clip and anti-creeping device shown in 50 Figs. 3 and 4; Fig. 9, is a plan view illustrating a further modification of my invention in which the anti-creeping device is designed to span the space between two ties and co-act with wear-plates carried by each of said ties; Fig. 10, is a perspective view of the form of 55 combined clip and anti-creeping device shown in Fig. 9, and Figs. 11, 12, 13 and 14,

are perspective views illustrating modified forms of washers which I may employ with my improved structure.

In the drawings, 1 represents the rail; 2 a 60 wear-plate, and 3 a tie upon which said wear-plate is mounted. The wear-plate may be secured to a wooden tie by means of bolts or lag screws 4 passing through the same, or when applied to a metallic tie, such as 3^a, the 65 wear-plate will be secured to a block 5 mounted on said tie, by means of bolts 4^a; both arrangements being substantially similar to the arrangement of fastening means illustrated in my patent above referred to. 70

Mounted upon the wear-plate and secured thereto in a suitable manner, is a special form of rail engaging member and clip serving as an anti-creeping device for the rail. This clip in the present instance comprises 75 a member having a portion 7 lying upon the wear-plate and arranged to extend over the flange of the rail; such portion having a serrated outward edge 8, with an overhanging lip 9; such portion of the structure 80 being substantially the same as that illustrated in my patent above referred to. In addition this clip member is provided with an upwardly projecting portion 10 lying against the web of the rail, and an overhanging 85 flange 11 at its side which engages the edge of the wear-plate. As the wear-plate is firmly secured to the tie, the flange 11 resists movement of the clip with respect to said wear-plate and prevents undue shear on the 90 means retaining said clip in place, while the upwardly projecting portion 10 fastened to the rail prevents longitudinal movement of the latter with respect to the tie. The portion 10 is apertured for the passage of one or 95 more bolts 12, whereby the structure may be secured to the rail. The outer edge of the clip extends diagonally with respect to the flange or shoulder 13 of the wear-plate, and wedge blocks 14, of the types illustrated in 100 my patent before referred to, are employed to adjust and maintain the clips in contact with the rail, such blocks thereby providing for lateral movement of the rail with respect to the wear-plate to adjust the gage of the 105 track. One of these clips will be mounted on each side of a rail at a given point when of the type illustrated in Figs. 1 and 2, and each clip will be fastened to the web of the rail substantially in the manner shown. 110

In Fig. 3, I have shown a modified form of structure; that is to say, it has a pair of rail

flange engaging portions 7^a with diagonally faced toothed portions for engagement with the wedge-blocks 14 whereby it is held to the flange of the rail; the wedge blocks being interposed between its diagonally faced toothed portions and the flange or shoulder 13 of said wear-plate. In this instance, the retaining members are held to the web of the rail by one or more bolts 12^a passing through the 10 portions 10^a of the same.

Fig. 4, is a cross sectional view on the line b—b, Fig. 3, showing the application of the structure to a wooden tie, and Fig. 5, is a sectional view on the line c—c, Fig. 3, illustrating the use of the flanges 11 at the sides of the retaining clips, (7 or 7^a), to engage the edges of the wear-plate 2.

The structure shown in Fig. 6, is substantially the same as that shown in Fig. 3, except that the wedge-blocks 14 are disposed to act toward each other, while those shown in Fig. 3 are arranged to act in the same direction.

The form of clip shown in Figs. 1 and 3, is fully illustrated by the perspective view, Fig. 7, while the double form of clip shown in Fig. 3, is fully illustrated by the perspective view, Fig. 8.

In Fig. 9, I have shown a further modification of my invention in which the combined clip and anti-creeping device is of such a size as to span or bridge two ties. These ties are provided with the usual wear-plates, and each end of the bridging member has the 35 notched or serrated portion for engagement by the wedge-blocks interposed between such portion and the flanges of the wear-plate. It will be understood that the structure shown in Figs. 9 and 10, if provided with additional 40 bolt holes, could be employed as a splice-bar. The clips are secured to the wear-plates by bolts 15, in the manner shown; the heads 16 of such bolts, whether rounded or substantially so, as shown in Fig. 2, or cylindrical, as 45 shown Figs. 4 and 5, are seated in similarly shaped recesses in the block 5, as in Fig. 2, or in the tie 3, as in Figs. 4 and 5. This construction provides means to assist the bolts 4 in holding the wear-plate 2 in position. The 50 bolts 15 are provided with squared nuts 18, as indicated, and to serve as retaining means for these nuts I may employ locking washers of the type illustrated in the perspective views, Figs. 11, 12, 13 and 14. These locking washers comprise flat plates, with portions or flanges to be turned up into engagement with the nut and portions to be turned down into engagement with the sides of the 55 clip or other portion of the structure held down by said nut. In Fig. 11, the washer is indicated at 20, and is substantially like those illustrated in the several views in engagement with the several nuts 18. It has flanges a, b and c, the flanges a and c engaging 60 the nut, while the flange b engages the

side of the clip. The washer 20^x, shown in Fig. 12, has a single flange a to engage the nut, and a single flange b to engage the clip. The washer 20^y, shown in Fig. 13, has a single flange d to engage the nut and a single flange b to engage the clip. The washer 20^z, shown in Fig. 14, has a pair of flanges a and c to engage the nut, and a pair of flanges b and d disposed at right angles thereto to engage the clip. The several flanges are bent on the 75 dotted lines.

In lieu of the form of wedge-blocks shown in the drawings, I may employ any of the forms shown in my patent before referred to; the engaging portion of the clip being 80 modified accordingly.

I claim:

1. The combination of a rail, a tie, a wear-plate mounted on the tie, a clip secured to the wear-plate and in engagement with the rail, said clip being movable whereby the rail may be adjusted with respect to the wear-plate, means for securing said clip to the web of the rail, and means carried by the clip in engagement with the wear-plate for 90 preventing movement of said clip with respect thereto and by its connection with the rail tending to prevent creeping of the latter.

2. The combination of a rail, a tie, a wear-plate mounted on the tie, a clip secured to the wear-plate and in engagement with the rail, said clip being movable whereby the rail may be adjusted with respect to the wear-plate, a bolt for securing said clip to 100 the rail, and a flange carried by said clip in engagement with the wear-plate, said flange preventing movement of the clip with respect to the wear-plate.

3. The combination of a rail, a tie, a wear-plate mounted on the tie, a clip secured to the wear-plate and in engagement with the rail, said clip having a pair of notched projections and being movable whereby the rail may be adjusted with respect to the 110 wear-plate, means for securing said clip to the rail, and means carried by each of said projections for preventing movement of said clip with respect to the wear-plate.

4. The combination of a rail, a tie, a wear-plate mounted on the tie, a clip, bolts for securing said clip to the wear-plate and in engagement with the rail, said clip having a pair of notched projections and being movable whereby the rail may be adjusted with 115 respect to the wear-plate, means for securing said clip to the rail, means for preventing movement of said clip with respect to the wear-plate, and wedge-blocks for engaging the notched projections of the clip and holding them in fixed relationship with the wear-plate.

5. The combination of a rail, a tie, a wear-plate mounted on the tie, a clip carried by the wear-plate and secured to the rail, said 130

clip being movable whereby the rail may be adjusted with respect to the wear-plate to adjust the gage of the track, notched projections carried by said clip, means for securing said clip to the rail, and depending flanges carried by said notched projections for engagement with the wear-plate and serving to prevent movement of said clip with respect to same.

10 6. The combination of a rail, a tie, a wear-plate secured to said tie, a clip mounted on the wear-plate and secured to the rail, said clip being movable whereby the rail may be adjusted with respect to the wear-plate, bolts for securing said clip to the wear-plate, and a flange carried by said clip in engagement with the wear-plate, said flange preventing movement of the clip with respect to the wear-plate parallel to the rail.

15 7. The combination of a rail, a tie, a wear-plate mounted on the tie, a clip secured to the wear-plate and in engagement with the rail, said clip having notched projections and being movable whereby the rail may be adjusted with respect to the wear-plate, means for securing said clip to the rail, and means carried by said projections for preventing endwise movement of said clip with respect to the wear plate.

20 8. The combination of a rail, a tie, a wear-plate secured to the tie, a clip, bolts for securing said clip to the wear-plate and in en-

gagement with the rail, said clip having notched projections and being movable whereby the rail may be adjusted with respect to the wear-plate, means for securing said clip to the rail, means for preventing movement of said clip with respect to the wear-plate, and wedge-blocks for engaging the notched projections of the clip and holding them in fixed relationship with the wear-plate, the latter having flanged abutments for said wedge-blocks.

25 9. The combination of a rail, a tie, a wear-plate secured to the tie, a clip carried by the wear-plate and engaging the rail, said clip being adjustable whereby the rail may be shifted with respect to the wear-plate to adjust the gage of the track, notched projections carried by said clip, means for securing said clip to the rail, and depending flanges carried by said notched projections for engagement with the wear-plate and serving to prevent movement of said clip with respect to the same and thereby re-55

sisting creeping of the rail.

In testimony whereof, I have signed my name to this specification, in the presence of two subscribing witnesses.

MAXIMILIAN F. BONZANO.
